UNITED STATES PATENT OFFICE.

JAMES C. PENNYPACKER, OF PHILADELPHIA, PENNSYLVANIA.

VEHICLE BUFFER.

Application filed July 22, 1926. Serial No. 124,117.

My invention relates to new and useful improvements in vehicle buffers, and has for its object to provide an exceedingly simple and effective device of this description, 5 which when applied to street railway cars, automobiles or like vehicles will enable the driver to prevent accidents from collisions, or greatly reduce the damage done in such collisions.

10 A further object of my invention is to so construct the device that it may be normally held out of action to avoid interference with traffic and yet instantly projected into operative position.

15 A still further object of my invention is to provide a simple and effective trip mechanism for releasing the buffer head.

With these and other ends in view, this invention consists in the details of construction and combination of elements hereinafter set forth and then specifically designated by 20 the claims.

In order that those skilled in the art to which this invention appertains, may understand how to make and use the same, I will describe its construction in detail, referring by numerals to the accompanying drawings forming a part of this application, in which:

30 Fig. 1, is a conventional showing of the front of a trolley car, with my improved buffer installed thereon.

Fig. 2, is a longitudinal section showing the buffer head in its inactive position and 35 the trip mechanism holding the spring compressed within the barrel.

Fig. 3, is a side elevation of Fig. 2.

Fig. 4, is a front end view of Fig. 3.

In carrying out my invention as here embodied, 40 11 represents a housing or barrel which is preferably cylindrical in shape, having its rear end closed by the cylinder head 12, the latter having a hole 13 through which slides the buffer rod 14.

45 Within the housing is confined a coil spring 15, through the center of which the buffer rod passes, and this rod has secured in any convenient manner upon its outer end the buffer head 16 against which the outer 50 end of the spring acts. The inner face of this buffer head is preferably recessed as indicated at 17, in order that the end of the spring may so seat therein as to maintain the head in alignment when being forced in or out. This arrangement obviates the necessity of otherwise guiding the rod 14.

Projecting from the side of the housing 11 are two lugs 18 in which the trip rod 19 is journaled, and this rod has a nose 20 upon its outer end adapted to be swung in front of the buffer head so as to hold said head in the position shown in Figs. 2 and 3, thus holding the spring 15 compressed within the housing; a collar 21 carried by the trip rod serving to prevent longitudinal movement of said rod.

22 is a crank carried by the inner end of the trip rod having an eye or other means of connection with an operating rod 23 for actuating the trip rod as and for the purpose hereinafter set forth.

The lugs or feet 24 project from the housing and are so placed as to be utilized for securing the device in the desired position on the car 25 by screws, bolts, straps or otherwise.

From the foregoing description the operation of my improved buffer will obviously be as follows:

Normally the spring 25 is compressed 80 within the housing and held in this position by the buffer head 16 being forced backward and secured against the action of the spring by the nose 20, but should a collision be imminent, it is only necessary 85 for the driver to pull upon the rod 23 to release the buffer head, which latter will be then projected forward beyond all the force of the spring, thus modifying the shock, which might otherwise seriously injure the 90 car and its passengers.

The outward stroke of the buffer head is limited by the nut 26 threaded upon the rod 14, and by adjusting this nut forward, projection of the buffer head may be determined.

After the buffer head has been utilized to avoid an accident, as just described, it is forced backward in any convenient manner, and latched in its inoperative position 100 by the nose 20, thus again holding the spring in compression and ready for further utilization.

In certain classes of vehicles, it may be desirable to use a number of these buffers, 105 in which case, actuating rods may be operated from a single source such as a lift lever.

The fact that the buffer head can be retracted prevents the interference with traffic 110 on crowded streets and in turning sharp corners, and yet permits its projection to

a considerable distance in front of the vehicle upon which it is carried, thus greatly reducing the tendency to serious accident, and as my improved buffer is of exceedingly simple construction, it is readily adapted for application to any form of vehicle.

Of course I do not wish to be limited to the exact details of construction as herein shown as these may be varied within the limits of the appended claims without departing from the spirit of my invention.

Having thus fully described my invention, what I claim as new and useful is:

1. A vehicle buffer comprising a housing; carrying means for securement to a vehicle; a coil spring guided within said housing; a buffer head in which one end of the spring seats; a rod carried by the buffer head and passing through said spring and head of the housing; a stop nut threaded upon the inner end of the rod; a trip rod journalled upon the housing; a nose projecting from one end of the trip rod and adapted to be swung into the path of the buffer head for

normally holding the latter against the compression of the spring; and means for swinging said nose out of engagement with the buffer head.

2. The herein described combination of a cylindrical housing having one end thereof closed with a cylinder head; a buffer rod passing through a suitable opening in said head; a buffer head secured upon the outer end of said rod; a spring coiled around said rod and interposed between said heads; a stop nut threaded upon the inner end of the housing; feet carried by the housing for securing the latter to a vehicle; a trip rod journalled in lugs carried by the housing; a nose projecting from the outer end of said trip rod; and a crank carried by the inner end of said trip rod for attachment to means for rotating the trip rod to latch and unlatch the buffer head.

In testimony whereof, I have hereunto affixed my signature.

JAMES C. PENNYPACKER.
